UNITED STATES PATENT OFFICE.

WILLIAM B. CHAPMAN, OF NEW YORK, N. Y.

APPARATUS FOR BURNING FINELY-DIVIDED COAL.

Application filed August 18, 1928. Serial No. 658,053.

The invention relates to the use of finely divided solid fuel such as slack, or ground coal, or sawdust, in boilers or furnaces, and has for an object to bring about the satisfactory combustion of all the fuel particles without requiring them to be dried and so finely and uniformly pulverized as is required for existing methods of burning pulverized coal; the necessity is thus obviated of conditioning the coal for the furnace by means of drying and pulverizing operations which are now so expensive as to prevent the general adoption of finely divided coal as a furnace fuel.

It is an object of the invention to burn finely divided coal while carried by or suspended in a rising air column of such a nature as to insure the proper combustion of substantially all of the fuel particles, even though they may vary in size.

Another purpose of this invention is to provide a suitable boiler setting and boiler so arranged as to make efficient use of the gases of combustion produced by an air column of the above nature.

The invention also aims to enable finely divided coal to be burned while carried by or suspended in an air column, without requiring preheating the air making up such column, although it is to be understood that preheated air may be employed if desired.

Further objects and advantages of the invention will be in part obvious and in part specifically pointed out in the description hereinafter contained, which, taken in connection with the accompanying drawings, discloses the invention as applied to certain different types of boiler; such embodiments of the invention, however, are to be considered as merely illustrative of its principles.

In the drawings:

Figs. 1, 2 and 3 are vertical sectional views showing different types of boilers adapted to be operated in accordance with the invention, also top feed, mid feed and under feed types of fuel feed.

In accordance with the present invention I provide an upwardly directed column of air traveling at a sufficient velocity to support or carry in suspension finely divided coal particles, and finely divided coal is fed into such column or carried along therewith, whereby the fuel particles may be burned

while so supported or carried in suspension. The column of air moves at a velocity which decreases as the air travels upwardly, whereby the lighter and more quickly consumed fuel particles will be supported and burned in the zone of combustion which exists at the upper portion of the column, and whereby the heavier or less easily ignited fuel particles, which tend to pass downwardly through and out of the zone of combustion, may be retained therein by reason of the greater velocity of the air in the lower portions of the air column. To burn eight-mesh coal for example it is only necessary to provide sufficient velocity of the air at the base or entrance end of the air column to hold the largest fuel particles in suspension, which particles in an ordinary furnace would fall to the bottom before their combustion was completed. According to the present invention the velocity of the heavier particles, which would tend naturally to increase as they fall, is arrested by the increased velocity of the air blast encountered, and the particles therefor become suspended in the air column.

In other words, if the fuel particles drop further into the air column, their velocity of fall tends to increase, but this greater tendency of the particles to fall is counteracted by the greater velocity of the air column which exists in the lower portion thereof.

If desired, the air which forms the above column may be preheated in any suitable manner, but in installations where preheated air is not desired to be used, the column may consist of air at ordinary temperature, since substantially all the fuel particles may be thrown into the zone of combustion and maintained therein until completely burned by the air column.

Fig. 1 illustrates the application of the invention to a simple boiler installation comprising a drum 1 having therein longitudinal heated gas passages (not illustrated) leading to a flue 2 at the forward end of the drum, and in communication at the rear end thereof with a combustion chamber 3 located below the drum.

The upwardly directed column of air above-mentioned is obtained by feeding air under pressure into an upwardly flared chamber 4, from air blast pipe 5 having a nozzle 6 disposed at the lower entrance end

of chamber 4. The chamber 4 is of restricted cross sectional area toward its bottom, and merges into the larger combustion chamber 3, constituting in effect an auxiliary or 5 preliminary part of chamber 3. Finely divided coal is fed into the chamber 4 in any suitable manner, as by feed worm 7 projecting into the chamber and connected to a hopper or the like (not illustrated) which 10 is kept supplied with finely divided coal.

The velocity of the air passing into chamber 4 is made sufficient at the lower end of the chamber to carry upwardly substantially all of the different sized pieces of fuel which 15 are fed into the air, but as the air column rises its velocity will progressively decrease owing to the expanding cross section of the chamber, with the result that in the upper section of the chamber the lighter fuel particles will be floated, and a zone of combustion 20 may be formed at this point which will extend far enough down into chamber 4 to burn the heavier fuel particles which are supported at a lower level where the velocity 25 of the air is greater. Combustion may be started for example by inserting a torch into the upper portion of chamber 4, and once the zone of combustion has been formed, the fuel will be burned continuously as it is supported by the air.

I prefer to employ in connection with the chamber 4, a means for conducting off slag or liquid ash which may be formed; in the embodiment illustrated in Fig. 1, inclined 30 troughs 8 are provided in the wall of the chamber adjacent to its upward end whereby liquid ash may be trapped in such troughs and conducted to an exterior chamber 9, which is shown as provided with a door 10. 35 The lower portion of chamber 4 is also shown as associated with a pit 11 from which access may be had to a trap 12 disposed beneath the chamber 4 and adapted to receive any refuse which may fall therefrom.

Fig. 2 illustrates the application of the invention to another type of boiler, in such manner as to utilize efficiently the heat of the gases of combustion. The boiler shown in Fig. 2 is provided with a drum 13 supported above a set of tubes 14 extending between front and rear headers 15 and 16 respectively. The air chamber 4^a is supplied at its lower end with air blast pipe 5^a and nozzle 6^a similar to the members 5 and 6 50 previously described, and finely divided coal is suitably fed into the chamber 4^a as by feed worm 7^a. In this instance the gases of combustion pass upwardly from chamber 4^a to the drum 13 and are deflected thereby to flow 55 past the tubes 14 in a downward direction, and through a dust pit 17 disposed beneath the tubes to an exhaust flue 18. Thus the heated gases instead of being exhausted at 60 the top of the boiler, pass off at the bottom 65 with the result that only the cooler gases

which have given up as much heat as possible in passing through the boiler, are withdrawn.

In the embodiment of the invention illustrated in Fig. 2 preferably means is provided to prevent the molten ash from collecting unduly around the walls of the chamber 4^a, such as the overhanging ledges 19 on the walls of the chamber, from which the slag may drop into a chamber 20. The inclined wall 21 of chamber 4^a furthermore is illustrated as provided with gaps 22 through which the slag may drop into a slag pit 23.

Figs. 1 and 2 show the invention as applied to certain types of boilers; In Fig. 3 I have illustrated the invention as combined with a type of boiler specially adapted to be used in connection therewith. According to this figure a boiler is employed having a drum 24 suitably supported within walls 25 and provided with an annular set of tubes 26 leading downwardly to an annular header 27. A chamber 4^b is disposed centrally beneath the drum 24 so that the gases of combustion rise upwardly in the chamber enclosed by the set of tubes 26 and over the top of an annular baffle 28, until they are deflected by drum 24 to flow downwardly past the set of tubes 26 and header 27 to an annular gathering chamber 29 at the bottom of the furnace and communicating with an exhaust flue 30.

The chamber 4^b is provided with gaps 22^a to permit the slag to drop from its walls into a slag pit, the chamber 4^b being frusto conical in shape as illustrated so that the gaps 22^a may extend entirely around its walls.

According to Fig. 3 furthermore air is fed into the bottom of chamber 4^b through a blast pipe 5^b into which finely divided coal is also fed, the coal being projected upwardly into chamber 4^b by the air, through or by a port 31 into which the pipe 5^b leads.

The apparatus of Fig. 3 is arranged to automatically control the area of opening through which the compressed air and finely divided coal is fed, according to the air pressure of the feeds; as shown, a regulator member 32 is guided by a rod 33 slidable in a spider 34 disposed in port 31, in such position that the member 32 tends to fall to a position in which it obstructs the passage of the air and fuel into conduit 4^b; the air pressure tends to lift the regulator member 32 and thus increase the area of the feed opening; the resultant area of opening therefore depends upon the balance of the above two features whereby when the apparatus is operated at a fraction of its full capacity a restricted area of feed opening maintains an air velocity which will be sufficient to lift and support the coal as desired; and if a certain amount of coal should pass into the central region of the chamber 4^b, where it will not be adequately supported, the regu-

lator will deflect it again into the annular feed opening surrounding the regulator, where the coal will be again projected upwardly.

5 In some instances the walls of the chamber 4 may converge to form an inlet opening at its bottom which is restricted in size both longitudinally and laterally of the furnace, resulting in a funnel-shaped chamber; and 10 in other instances two of the side walls of such chamber may be parallel and spaced apart approximately a distance equal to the width of the furnace, in which case the inlet opening at the bottom of the chamber will be elongated or slotlike in cross section. In 15 the latter case the pipe 6 may be omitted and the air merely projected into the chamber 12 through the pipe 5, after which the air will pass upwardly into the chamber 4 through 20 the slotlike inlet opening thereof.

While certain embodiments of the invention have been disclosed, it will be obvious that many changes may be made therein without departing from its principles, as 25 defined in the appended claims.

I claim:

1. An apparatus for burning finely divided solid fuel comprising an upwardly directed chamber, means for conducting air under pressure into the lower portion of such chamber, said apparatus including means whereby finely divided solid fuel may be fed into said chamber, and means for conducting liquid ash from off points on the side 35 wall of such chamber which are without the direct range of action of the air blast.

2. An apparatus for burning finely divided solid fuel comprising an upwardly directed chamber of cross sectional area increasing toward the top thereof, means for conducting air under pressure into the lower portion of such chamber, said apparatus including means whereby finely divided solid fuel may be fed into such chamber, and 40 means for conducting liquid ash from off points on the side wall of such chamber which are without the direct range of action of the air blast.

3. The combination set forth in claim 2, 50 wherein the wall of the chamber is provided with a gap adapted to permit liquid ash to drop from off such wall.

4. An apparatus for burning finely divided solid fuel comprising an upwardly directed chamber of restricted cross sectional area toward its bottom and provided with a restricted bottom opening, means for admitting fuel to said chamber and for conducting air under pressure into the lower portion of 55 such chamber to float the finely divided fuel, means disposed in the hot portion of said chamber for drawing off liquid ash from the walls thereof, a combustion chamber disposed adjacent the upper portion of said first 60 mentioned chamber, said apparatus includ-

ing a boiler having heating tubes and passages adapted to conduct the gases of combustion from the upper portion of said first mentioned chamber past said tubes and finally in a downward direction whereby said 70 gases are exhausted at a low point in their travel through the boiler.

5. The combination set forth in claim 4, together with a gathering chamber disposed adjacent the bottoms of the tubes, and 75 wherein the heating tubes are disposed about the upper portion of the first mentioned chamber in claim 4, to enclose the gases of combustion projected upwardly from the chamber, and said passages conducting the gases downwardly through an 80 annular path past the tubes to said gathering chamber.

6. An apparatus for burning finely divided solid fuel comprising an upwardly directed chamber of restricted cross sectional area toward its bottom and provided with a bottom opening, means for conducting air under pressure upwardly through said opening, said apparatus including means whereby finely divided solid fuel may be fed into such chamber and means for automatically controlling the cross sectional area of the air column passing upwardly into said chamber in accordance with the amount of 90 air being fed therethrough.

7. The combination set forth in claim 6, 100 wherein the last-mentioned means is constituted by a floating regulator member in the entrance opening of such chamber.

8. An apparatus for burning finely divided solid fuel, comprising an upwardly directed chamber of cross sectional area which is relatively small at the bottom and greater toward the top thereof, said apparatus including means whereby finely divided solid fuel may be fed into such chamber, and means associated with the lower portion of said chamber for conducting air under pressure into the lower part of such chamber and 110 for distributing the force of the air blast toward the walls of such conduit.

9. An apparatus for burning finely divided solid fuel, comprising an upwardly directed chamber of cross sectional area which 115 is relatively small at the bottom and greater toward the top thereof, said apparatus including means whereby finely divided solid fuel may be fed into such chamber, and means for conducting air under pressure 120 into the lower part of such chamber and for intensifying the air blast toward the lower portion of the walls of the chamber.

10. An apparatus for burning finely divided solid fuel, comprising an upwardly directed chamber of cross sectional area increasing toward the top thereof, means for conducting air under pressure into the lower part of such chamber, said apparatus including means whereby finely divided solid fuel 130

may be fed into such chamber, and a deflector member located in the lower portion of such chamber and acting to deflect the air blast toward the lower portions of the walls of the chamber.

11. An apparatus for burning finely divided solid fuel comprising an upwardly directed chamber of restricted cross sectional area at its bottom, and also provided with an opening of restricted size at its bottom, means for conducting air under pressure upwardly through said opening into said chamber, said apparatus including means whereby finely divided solid fuel may be fed into said chamber to be supported by the upwardly moving column of air therein, and means adjacent the said bottom opening for altering the cross sectional area of the air column which moves upwardly into the chamber.

12. An apparatus for burning finely divided solid fuel in suspension, comprising a

combustion chamber, restricted at its base to form a relatively small fuel and air feed opening at the bottom, a boiler having tubes 25 surrounding said combustion chamber, said boiler also over-lying the top of the combustion chamber, means associated with said feed opening for distributing the fuel and air fed in through said opening toward the 30 side walls of said combustion chamber whereby the products of combustion are directed upward toward the tubes in said combustion chamber, said apparatus being provided with an annular passageway enclosing said combustion chamber and including said tubes to lead the products of combustion downwardly along said tubes, and an outlet 35 flue for the spent gases disposed adjacent the bottoms of the tubes. 40

In testimony that I claim the foregoing, I have hereunto set my hand this 15th day of August, 1923.

WILLIAM B. CHAPMAN.
